UNITED STATES PATENT OFFICE.

JOHN PRITCHARD WILLIAMS, OF NEW YORK, N. Y., ASSIGNOR TO DUPLEX ELECTRIC COMPANY, A CORPORATION OF DELAWARE.

CONTACT MECHANISM FOR ELECTRIC ALARM SYSTEMS.

1,146,294.

Specification of Letters Patent. Patented July 13, 1915.

Application filed October 18, 1913. Serial No. 795,832.

To all whom it may concern:

Be it known that I, JOHN P. WILLIAMS, a citizen of the United States, and resident of New York, in the county and State of 5 New York, have invented certain new and useful Improvements in Contact Mechanisms for Electric Alarm Systems, of which the following is a specification.

This invention relates to contact mechanisms 10 for electric alarm systems and it has particular relation to an improved construction and arrangement of contact mechanism in connection with the alarm circuit of an electrical burglar-alarm system, whereby the 15 circuit may be operated to actuate the alarm.

The object of my invention is to provide a simple and improved contact mechanism 20 of the class set forth, which will be more effective and positive in operation, which can be operated with greater certainty and convenience, and which will possess advantages in point of simplicity, effectiveness, and general efficiency.

25 The improved contact mechanism comprising my present invention is designed to be used in connection with the alarm circuit of any general type of burglar-alarm systems such as are now employed, especially 30 in connection with "daylight holdup systems" which are employed for the protection of banks or apartments for the storage of valuables, the contact mechanism being conveniently arranged with relation 35 to the desk or location of a cashier or teller or other operative and being adapted to be instantly and effectively operated with certain action. The improved contact mechanism is adapted for operation with relation 40 to either an open or a closed circuit, its structural relation and connection with a normally-open circuit being herein shown, and it may be placed on the floor under the desk of a cashier or teller or other operative, or in a suitable location upon the wall, or in any other desirable or adapted position. For instance, the mechanism may be arranged directly on the desk, and concealed from view, or in a grille-work such as is employed 45 to surround desks or compartments in banking rooms, in which latter instance

the operating bar of the contact mechanism could be arranged to constitute a part of the grille-work. The operating bar, as comprised in the improved mechanism, can be 55 adapted to be conveniently operated by the foot or hand, according to the location and conditions under which the mechanism is employed.

Heretofore, in contact mechanisms of this 60 class, a single contact push button has been usually employed, for instance, at a point on the floor and adapted to be operated by foot pressure, but these conditions render it difficult for the operator to locate the small 65 area of a single push button and the necessary quick action in causing the alarm is not insured.

My improvements are designed to overcome all the disadvantages and conditions 70 as thus heretofore encountered in the push button arrangements of alarm systems of the class to which my invention relates, and to effectively avoid any delay in the operative action to cause the alarm, the im- 75 proved mechanism enabling the operator to instantly locate and operate the contacts by means of the operating bar which, in the form and construction of my invention as herein illustrated, is common to a plurality 80 of contacts or push buttons and may extend the full length of a desk or other position in which it is located, substantially as hereinafter described.

In the drawings—Figure 1 is a top or 85 plan view of the improved contact mechanism, as installed upon the floor, the operating bar being in normal position. Fig. 2 is a view corresponding to Fig. 1, showing the operating bar in raised position and out 90 of operative relation to the contacts. Fig. 3 is an end view of the mechanism as shown in Fig. 1, the position as shown in Fig. 2 being illustrated in dotted lines. Fig. 4 is a detail cross-section on the line $x-x$ Fig. 1, 95 illustrating one type of contact or push button as employed in the mechanism, and the connection thereof with an alarm circuit. Fig. 5 is a sectional view corresponding to Fig. 4 and illustrating a modified construction in which the contact is directly 100 carried by the operating bar.

Corresponding parts in all the figures are denoted by the same reference characters.

Referring to the drawings, 1 designates one of the plurality of contacts or push buttons as employed in my invention, which may be of any suitable or adapted construction and is carried by a suitable boxing or housing, 2, which is secured to the floor or at any other desired point of location. In 10 the preferred construction, as herein illustrated, the body of the housing 2, has an inclined top surface, as at 3, to more effectively meet the angle of pressure when the mechanism is operated by the foot, and it is provided with lateral base flanges, as at 4, through which pass securing screws, 5. The preferred construction of contact or push button, as illustrated in Fig. 4, comprises a 15 slideable stem, 6, projecting through an opening, 7, in the top of the housing 2, and through an opening, 8, in the bottom of a tubular member, 9, interiorly carried by said housing. The projecting top end of said stem 6 carries a head, 10, to provide an 20 enlarged area for operative contact with the operating bar, and its bottom projecting end is adapted to enter between two spring plates, 11-11, secured to and projecting downwardly from opposite sides of said 25 tubular member 9. The contact or push button 1 is spring-controlled by means of a coiled spring, 12, accommodated within the tubular member 9 and surrounding the stem 6 and arranged between the bottom wall of 30 said tubular member and a lateral flange, 14, carried by the stem 6 within the internal chamber of the member 9, the chamber and said flange 14 being of greater diametrical area than the openings 7 and 8. Thus, when 35 in normal position, the lower projecting end of the stem 6 is out of engagement with the spring plates 11, and when the contact 1 is depressed said lower end will enter between said spring plates and thus close the alarm 40 circuit, the contact being returned to normal 45 position and the alarm circuit again opened by action of the controlling spring 12, when pressure is removed, it being understood that normally the ends of the spring plates 50 11 are not in contact and that the circuit is open at this point.

I have herein illustrated one form of alarm circuit of adaptable type, in connection with the contact mechanism, as follows: 55 From connection with one of the plates 11 a wire, 15, extends to one side of a battery, 16, and from the other side of the battery a wire, 17, extends to the frame of an automatic drop, 18, and from the contact, 19, of 60 said drop a wire, 20, extends through the coils of said drop and to the other spring plate 11. It will be understood that the spring plates 11 are insulated, as at 21, from 65 their carrying member 9, and that the circuit through the automatic drop is normally

open at said spring plates but is completed and closed when the stem 6 of the contact member or push button 1 enters between the lower ends of said plates. A branch alarm circuit is arranged in connection with the 70 circuit just described and is constituted by a wire, 22, extending from the wire 15 to a bell or other signal device, as at 23, and a wire, 24, extending from said signal device to a contact, 25, adjacent said automatic 75 drop. Thus, in operation, when the main circuit through the battery is closed, as above described, the automatic drop is energized and its contact arm is permitted to drop from the contact 19 to contact with the 80 contact 25 of the branch alarm circuit, and the circuit is then completed through the bell or signal device 23, and the latter operated, as follows: from one side of the battery 16 through the wires 15 and 22 and 85 through the bell or signal device 23 and the wire 24 to the contact 25 and then through the arm and frame of the automatic drop and through the wire 17 to the other side of the battery 16, and the alarm will be actuated until the automatic drop is manually reset. The alarm circuit and alarm mechanism may be suitably arranged as desired in concealed or inclosed position, as is usual in burglar-alarm systems of the class for which 90 my present improvements are adapted.

It will be understood that in the employment of a plurality of contacts arranged in parallel, as herein described, with relation to the depressible operating bar, each of said 100 contact devices comprised in the set will be in the alarm circuit, by arrangement in parallel in the circuit completed by the wires 20 and 15, in the manner as illustrated in 105 Figs. 4 and 5 in which one of said contact devices is illustrated in circuit upon said wires 20 and 15.

In carrying out my invention, the contact or push button devices, as hereinbefore described, are preferably arranged in a plurality with relation to the operating bar, so 110 that the latter is in operation common to such plurality of contacts.

It will be understood that the employment of merely a single push button contact designed to be operated by means of direct foot or finger pressure upon the contact, as in the usual alarm mechanism constructions, renders it difficult for the operator to locate the single push button under conditions of 115 immediate emergency, and this objection is effectively overcome in my invention and improvements by providing the operating depression bar having an extent with relation to the contact alarm mechanism which will 120 enable the operation of the latter by pressure upon the bar at any point. This depression bar can thus be readily located and operated at any point throughout its extended length, and in relation to these conditions of opera- 125 130

tion a plurality of contacts arranged in parallel are employed and subject to the operation of the extended bar in common to said plurality of contacts, the latter being related to the longitudinal extent of the bar so that depression of the same at any point will be operative upon at least one of said contacts under any flexible action of the bar. Thus, if the bar is depressed at merely one end, 5 it will be operative upon the contact or contacts located with relation to that end, even though it is not operative upon the contact or contacts located at the opposite end, and the same operative conditions will result for 10 the effective operation of at least one of the plurality of contacts if the bar is operated at its central portion or at any other point of its longitudinal extent. By the employment of a plurality of contact devices arranged in 15 parallel, advantages in point of effectiveness and certainty of operation are secured, and this parallel electrical arrangement of contacts is especially desirable in view of the extended length of the operating bar in its 20 action in common to the plurality of contacts, which length, it will be understood, is considerably extended under some conditions of installation of the mechanism. Furthermore, the plurality of contacts in relation to 25 the extended operating bar has the additional advantage that if one or more of the contacts are for any reason inoperative, or the degree of pressure thereon is not sufficient to cause their operation, at least one or 30 more of the contacts which are directly related to the point at which the bar is depressed will be operative with certainty.

The operating rod or bar, 26, extends longitudinally of the mechanism, and may, for 35 instance, extend the full length of a desk, thus enabling the immediate operative location of the bar to effectually actuate the contacts or push buttons and enabling effective operation at any point throughout the length 40 of the bar. The operating bar is normally in position over the set of contacts 1 and resting upon the heads 10 of the same (as shown in Fig. 1) and it is pivotally mounted to provide for its operative movement under 45 pressure to depress the contacts 1. The pivotal mounting of the bar is also preferably such that it may be thrown over out of operative position with relation to the set of contacts 1 (as shown in Fig. 2) when the 50 mechanism is out of use, and in the preferred construction for this purpose the operating bar is hinged in connection with the boxings or housings 2 at the respective ends of the set of contacts with relation to which 55 the bar is mounted, the hinged or pivotal connections being constituted by plates, 27, pivoted, as at 28, to the outer side walls of the body of the housings 2, at the rear of the latter, and having the respective ends of the 60 operating bar 26 suitably secured to the free ends of said plates. The hinge-plates 27 preferably have an angular edge contour, approximating a triangle with straight edge, as at 29, at the vertex of the angle, whereby when the operating bar 26 is thrown over 65 and back into non-operative position the edge 29 will rest upon one of the lateral base flanges 4 of the housing 2 and support the pivotally-mounted bar 26 in the position shown in dotted lines in Fig. 3. To retain 70 the bar 26 in operative position and to prevent its displacement or accidental throwing back to non-operative position, a holding or locking means is provided and preferably consists of a lever, 30, pivotally fulcrumed, 75 as at 31, upon the top surface 3 of the housing 2 and having an angular end, 32, arranged to engage the angle edge, 33, of the hinge-plate 27 when the mechanism is in normal operative position. This locking 80 lever 30 is conveniently arranged so that it may be manipulated to release the operating bar and permit the latter to be thrown back to the position shown in dotted lines in 85 Fig. 3, but will, when in active position, retain said bar in effective relation to the set of contacts 1.

In Fig. 5 I have illustrated a modified construction in which the contacts 1 are directly carried by the operating bar 26. In 90 this construction the stems 6 of the contacts 1 are secured at their top ends to the bar 26, and carry a flange, 34, adapted to pass through the top opening 7 in the housing 2 and bear upon a follower-plate, 35, 100 slidably mounted within the internal chamber of the tubular member 9 and acting upon the coiled spring 12, the follower-plate being of greater diameter than the top opening 7. Thus, in operation, the spring control of the contacts 1 is the same as in the construction illustrated in Fig. 4, and the general operation of the mechanism is also the same as that hereinbefore set forth. This modified construction is of particular 105 advantage under circumstances where the improved contact mechanism is located on the floor, as it permits the raising of both the operating bar 26 and the contacts 1 (the latter being carried by the bar) from operative position, which is convenient under some conditions of use, for instance, at night or when it is desired to retain the mechanism out of use, or when the floors are being cleaned or swept, to prevent the accidental actuation of the alarm by pressure upon the contact or push button devices.

I do not desire to be understood as limiting myself to the detail construction and arrangement of parts as herein shown and described, as it is manifest that variations and modifications therein may be resorted to, in the adaptation of my invention to varying conditions of use, without departing 115 from the spirit and scope of my invention.

tion and improvements. I therefore reserve the right to all such variations and modifications as properly fall within the scope of my invention and the terms of the following 5 claims.

Having thus described my invention, I claim and desire to secure by Letters Patent:

1. An electrical contact mechanism of the class described, comprising a plurality of 10 de-pressible contacts, an operating bar extending longitudinally thereof and operative in common thereto to depress the contacts, and pivotal means carrying said depression bar and fulcrumed to bring the bar at one terminus into operative position directly over said contacts and to bring the bar at the other terminus to an inoperative position entirely away from the plane of the contacts when the mechanism is out of use, substantially as and for the purpose set forth.
2. An electrical contact mechanism of the class described, comprising a plurality of de-pressible contacts, an operating bar extending longitudinally thereof and operative in common thereto to depress the contacts, pivotal means carrying said depression bar and fulcrumed to bring the bar at one terminus into operative position directly over said contacts and to bring the bar at the other terminus to an inoperative position entirely away from the plane of the contacts when the mechanism is out of use, and means for retaining said swinging depression bar in its terminal operative position directly over the contacts.
3. An electrical contact mechanism of the class described, comprising de-pressible contact means, an operating bar pivotally mounted in operative relation to said contact means, and hinge-members carrying said bar and having their pivot relatively arranged to swing said bar in an arc to and from said contact means to bring the depression bar at one terminus of the arc into operative position directly over said contact means and to bring the bar at the other terminus to an inoperative position entirely away from the plane of the contact means when the mechanism is out of use.
4. An electrical contact mechanism of the class described, comprising de-pressible contact means, an operating bar pivotally mounted in operative relation to said contact means, hinge-members carrying said bar and having their pivot relatively arranged to swing said bar in an arc to and from said contact means, and a lever fulcrumed to engage the hinge-member to retain said swinging operating bar in normal operative position.
5. An electrical contact mechanism of the class described, comprising de-pressible contact means, a boxing or housing carrying contact means, a bar operative to depress said contact means, and means pivotally carrying said depression bar and fulcrumed upon said housing to bring the bar at one terminus into operative position directly over said contact means and to bring the bar at the other terminus to an inoperative position entirely away from the plane of the contact means when the mechanism is out of use.
6. An electrical contact mechanism of the class described, comprising de-pressible contact means, a boxing or housing carrying contact means, an operating bar pivotally-mounted upon said housing and operative to depress said contact means, and means carried by the housing and operative to retain said pivoted bar in its operative position over said contact means when the mechanism is in use.
7. An electrical contact mechanism of the class described, comprising de-pressible contact means, a boxing or housing carrying contact means, said housing having an inclined surface relative to said contact means, and an operating bar pivotally mounted to swing over said inclined surface in operative relation to said de-pressible contact means to depress the same.
8. An electrical contact mechanism of the class described, comprising a plurality of de-pressible contacts, boxings or housings projectively carrying said contact means, a bar extending longitudinally of said de-pressible contacts and operative in common thereto to depress the contacts, and means pivotally carrying said depression bar and fulcrumed upon said housings to bring the bar at one terminus into operative position directly over said contacts and to bring the bar at the other terminus to an inoperative position entirely away from the plane of the contacts when the mechanism is out of use.
9. An electrical contact mechanism of the class described, comprising an operating bar extending longitudinally of the mechanism, pivotal means carrying said bar and fulcrumed to bring the bar at one terminus into operative position with relation to contact means and to bring the bar at the other terminus to an inoperative position entirely away from the plane of such contact means when the mechanism is out of use, and contact means operative by depression of said bar in its pivotal movement.
10. An electrical contact mechanism of the class described, comprising a plurality of de-pressible contact means, said contact means being arranged in electrical parallel connection, a de-pressible cross member extending longitudinally of said contact means and above the same and operative in common to bear upon the same, and pivotal means carrying said depression cross member and fulcrumed to bring the same at one

terminus into operative position directly over said contact means and to bring the cross member at the other terminus to an in-operative position entirely away from the plane of the contact means when the mechanism is out of use.

In testimony whereof I have signed my

name in the presence of the subscribing witnesses.

JOHN PRITCHARD WILLIAMS.
